PUMP

Application filed July 25, 1930. Serial No. 470,559.

This invention relates to improvement in pumps.

In centrifugal pumps of the self priming type, a quantity of liquid is trapped in the pump when it is shut down and when the pump is re-started this liquid is whirled by the runner to entrain air and draw vacuum into the pump. The mixture of air and liquid is discharged from the pump into a separator in which the gas entrained in the liquid is permitted to escape therefrom and the liquid is returned to the pump to be recirculated by the runner and again discharged into the separator. In pumps of this kind, it is essential that the throat through which the mixture is discharged be of such cross sectional area that the mixture discharged during priming will completely fill it and thereby seal it against the gas in the separator from being forced into the pump by the pressure built up in the separator by the discharge of the mixture into it. It is furthermore essential in the priming of a pump of this kind that a certain quantity of liquid be returned to the runner channel for mixing with the gas in that channel. If this quantity of liquid is excessive the pump becomes drowned and incapable of drawing a higher vacuum on its intake or suction side. If the quantity of liquid is insufficient the pressure in the separator forces the mixture and gas back into the runner channel and the vacuum which has been drawn therein is consequently reduced.

In the prior art of which I am aware various arrangements have been provided to regulate this return flow of liquid and to insure that the main discharge throat of the pump will be completely sealed by the mixture of gas and liquid discharge from the runner. In certain of these prior art pumps, it has been noted that the pump will start drawing a vacuum, proceed successfully in this manner for a short interval of time, then drop its vacuum, and subsequently again continue with the drawing of a vacuum in the runner channel. This operation produces a surging in the pump and it has been noted that this surging is due to a variation

in the rate of return of liquid to the runner channel from the separator.

In a properly designed pump, the quantity of mixture generated by the runner is more than can be carried by the main discharge throat and a portion of this liquid is thrown over into the return channel where it builds up a pressure that opposes the return of gas free liquid from the separator. If the liquid in the runner channel becomes excessively high, the quantity of mixture thrown into the return port is great and the return of gas free liquid to the channel is thereby diminished. In certain instances its return flow may be momentarily entirely cut off with the result that the excess quantity of liquid in the channel is soon exhausted and the quantity of mixture thrown into the return throat thereby greatly diminished or entirely eliminated. As a result gas free liquid flows rapidly into the runner and a cycle of the surge is thus completed.

In my present invention I have corrected this tendency of a centrifugal pump to surge during its priming period by providing the usual discharge port of such cross sectional area that it can be readily maintained full of mixture by the runner during the priming period. I also provide the usual return passage through which gas free liquid is returned to the runner in a path substantially radial of that runner. I also provide a baffle or baffles in the return throat which divides that throat into two or more sections. The mixture thrown into the return passageway by the runner strikes against this baffle and is thereby deflected into such a path that it is incapable of completely shutting off the return flow of gas free liquid to the runner. While the mixture is incapable of completely shutting off the flow of gas free liquid, it is still capable of opposing that flow to thereby form a hydraulic valve which regulates the return flow of gas free liquid so that the ratio of liquid to gas in the runner chamber can be accurately maintained at the proper value for the efficient drawing of a vacuum by the pump. Since the return flow of gas free liquid is never interrupted, there will always be sufficient liquid in the channel to enable

the pump to increase its suction and the tendency of the pump to surge during its priming period is thereby eliminated.

In the prior art pumps of this class, the 5 separator has invariably been a large and bulky structure often times much larger than the pump itself, this size in the separator being necessary to permit complete escape of gas from the mixture to thereby provide 10 a gas free liquid for returning to the runner channel. Usually the separator is a separate device suitably attached to the pump, and in my present invention I have provided a new and improved separator of this type, one 15 which is more efficient and therefore capable of being built as a unit substantially smaller than the separators used heretofore, such reduction in size being accomplished without a reduction in the efficiency of the separator. 20 Separators in the prior art have provided for whirling the mixture discharged by the pump runner about an axis located substantially normally to the axis of rotation of the runner. I have found that by providing a 25 separator in which the axis of the whirling mixture is parallel to and above the axis of the rotating runner, the over-all dimensions of the separator can be materially reduced without reducing its efficiency in any way. 30 Other advantages resulting from this construction will be apparent from a reading of the detailed description and claims which follow.

Now to acquaint those skilled in the art 35 in the teachings of my invention, reference is made to the accompanying drawings in which a preferred embodiment of it is shown by way of example and in which:

Figure 1 is an elevational view, partly in 40 section, of a pump and separator;

Figure 2 is a cross sectional view taken along the line 2—2 of Figure 1;

Figure 3 is a cross sectional view taken along the line 3—3 of Figure 2;

45 Figure 4 is a cross sectional view taken along the line 4—4 of Figure 1 and showing the return passageway;

Figure 5 is a similar view taken along the line 5—5 of Figure 1 showing the discharge 50 passageway;

Figure 6 is a cross sectional view taken along the line 6—6 of Figure 2 looking into the direction of the arrows;

Figure 7 is a fragmentary cross sectional 55 view taken along the line 7—7 of Figure 2 looking in the direction of the arrows; and

Figure 8 is an elevational view of a modified form of separator.

60 Referring to the drawings now in more detail, the pump comprises a casing 1 consisting of a generally cylindrical casting which may be supported upon feet 2—2 and which contains a central cylindrical runner channel 3 in which the runner or impeller 4 is supported to rotate about a horizontal axis.

The runner casing 1 is provided with an inlet cover 5 which is preferably of conical shape and adapted to be bolted to the casing 1 by a plurality of bolts 6 which are extended through the flanged periphery of the cover 5 and through registering openings 7 in the casing 1.

70 The cover plate 5 is provided with an inlet port 8 around which the flange 9 extends to form a mounting for the inlet trap of the pump.

75 The inlet trap is not of the essence of the present invention and any preferred type of inlet trap may be used, for example the inlet trap shown in my copending application Serial No. 374,409, filed June 28, 1929 (Case 29) may be successfully employed within the teachings of my invention. The use of bolts 6 to attach the cover 5 to the pump casing 1 is optional, as the member may be secured together by any other suitable arrangement such as the clamps shown in my above mentioned copending application. Preferably the cover plate and casing are both castings made of metal suitable for the use to which the pump is to be placed, the metal preferably being iron when the pump is to be employed in pumping noncorrosive liquids and of being an acid resisting alloy if the pump is to pump corrosive liquids.

80 The pump casing 1 is also provided with a discharge throat 11 which is formed in the walls of the casing itself. This discharge throat leads tangentially out of the runner channel 3 and is provided with a restricted port or opening 12 adjacent the peripheral edge of the runner 4. The cross sectional area of this port is carefully calculated with respect to the impeller speed and pump capacity and the flare of the throat 11 to increase its cross sectional area likewise carefully proportioned to the cross sectional area of the port. The outer wall 14 of this discharge 85 throat is straight and is disposed as a tangent to the runner channel 3, and the increase in cross sectional area of the throat is obtained by suitable shaping of the opposite wall 15 which defines the passageway.

90 The pump casing 1 is also provided with a return passageway 16 which is formed in the projection of the casing 1 which houses the discharge passageway 11, this return passageway being formed between the wall 17 which is located substantially radially of the runner 4 and the wall 18 located substantially tangential to the runner. A dividing baffle 19 or plurality of such baffles separates the return passageway 16 into a plurality of portions, for a purpose which will be hereinafter explained. The number of such passageways varies with the capacity of the pump and the two shown in the drawings are shown by way of example only.

95 The cross sectional area of the return passageway 16 and of its component parts located on opposite sides of the baffles 19 is less 100

than the cross sectional area of the main discharge throat 11, and the walls 17 and 18 are so shaped that the return passageway 16 has its maximum cross sectional area at the upper 5 flange 13 of the pump.

The upper surface of the flange 13 is machined flat to provide a seating surface for the separator which is attached thereto, the flange 13 preferably being provided with a plurality of holes, not shown, through which suitable bolts are projected to attach the 10 separator to the casing.

The separator indicated generally at 20 consists of a cylindrical drum 21 from the 15 lower side of which the inlet passage 22 and the outlet passage 23 are projected. The wall 24 of the separator is a flat wall terminating in the flange 25 which registers with the flange 13 of the pump casing. The inner surface of the wall 24 accurately aligns 20 with the inner surface of the wall 14 of the pump casing and is therefore tangential to the pump runner 4. The upper part of the separator consists of a cylindrical wall section 26 joined at one end with the straight wall section 24 and at the other end with a second straight wall section 27, which latter section terminates in a continuation 25' of the flange 25 which in turn registers with the 25 flange 13 on the pump casing.

At the bottom of the separator and between the walls 24 and 27 is a triangular wall member one side 28 of which forms a bounding wall of the inlet passage 22, and the other 30 wall 29 forms a bounding surface of the outlet 23 of the separator. The third wall 30 of this triangular member is arcuate and its center coincides with the center of the cylindrical wall 26 thereby completing the cylindrical 35 chamber at the upper part of the separator.

As will be seen in Figure 3 the straight wall sections 24 and 27 and the cylindrical wall section 26 are joined by side walls 31 40 and 32 which together with the wall sections 24, 26 and 27 form the separator as a substantially cylindrical member whose axis is parallel to the axis of the pump runner.

Side walls 31 and 32 are provided with lateral ports 33 and 34 over which are cast the 45 walls 35 and 36 of the discharge duct 37, this duct branching out of the central chamber 21 of the separator laterally at the upper part of that chamber and then preferably extending 50 transversely of the chamber 21 across the top of it and above the cylindrical wall 26. The discharge duct 37 terminates in a flange member 38 which is provided with suitable holes through which a discharge pipe may be 55 connected to the separator in any preferred manner such as by bolting. Obviously the shape and position of the duct may be altered within the teachings of my invention, and the position of the flange 38 may also be 60 changed. In certain instances it may be ad-

vantageous to place this flange 38 in a horizontal position above the separator or to one side of it, so that the discharge pipe, not shown, may be led vertically from the pump.

The walls of the separator are provided with threaded openings 40 and 41 located substantially at the junction of the straight wall sections 24 and 27 and the cylindrical wall section 26, these openings being provided with threaded plugs 42 which are normally in place to seal the openings. These openings permit inspection and cleaning of the separator when necessary. The triangular member consisting of walls 28, 29 and 30 is provided with a central opening 43 which is so placed merely to reduce the amount of metal and consequently the weight of the separator; this opening of course can be omitted if desired within the teachings of my invention.

In the operation of the pump and separator shown in the drawings, when the pump is shut down a certain amount of liquid is trapped in the pump and the inlet trap, not shown, and when the runner 4 is revolved this liquid is circulated to entrain gas in it thereby forming a mixture which is expelled from the peripheral portion of the runner through the throat 12, the discharge duct 11 into the inlet 22 of the separator. This mixture of 95 gas and liquid is traveling at a high speed and as it passes through the restricted area of the throat 12 it is squeezed somewhat and completely seals that port against the entrance of gas or liquid from the separator. As the liquid travels into the larger portion 100 11 of the discharge throat it is permitted to expand somewhat thereby permitting the gas in it to collect in the form of bubbles in which condition it is better able to escape from the liquid.

As the liquid is thrown tangentially from the runner it flows along the tangential walls 14 and 24 until it strikes the cylindrical wall 26 which bends it in an arcuate path whose axis is parallel to the axis of the pump runner.

The bending of the mixture of gas and liquid in an arcuate path causes the heavier liquid of the mixture to hug the outside wall producing thereagainst a stratum of gas free liquid. The lighter gas and mixture of gas and liquid flows along the inside of the arcuate path forming a layer or stratum of mixture beneath and inside of the stratum of solid liquid. In Figure 1 I have illustrated this action by the closed barb arrows 80 representing the mixture of gas and liquid, and the open barb arrows 81 representing the gas free liquid. Thus it will be seen that as the mixture flows upward from port 12 through throats 11 and 22, no separation occurs. As the mixture is bent in an arcuate path by the wall 26, the heavier gas free liquid, arrows 81, is thrown to the outside of the path, and

the mixture is therefore forced to the inside of that path. By the time the mixture has reached the uppermost portion of the wall 26, this separation is quite complete and strata 5 of liquid and mixture are clearly formed. Some of the gas in the mixture is separated from the liquid during this stratification readily escapes laterally through the ports 33 and 34 and thence into the discharge duct 10 37 from which it escapes from the pump through the discharge piping, not shown.

With the stratum of solid liquid above and outside of the stratum of gas and liquid, gravity separation of the gas from the liquid 15 is greatly hindered. As the mixture and solid liquid flows onward around the arcuate path 26 and against the wall 27, the relative position of the two is reversed so that the solid liquid is beneath the mixture and free 20 separation of the gas from the liquid by gravity is thereby enhanced.

By the time the mixture and solid liquid have reached the wall section 27 of the separator they have lost the greater part of the 25 velocity imparted to them by the runner so that their movement is at a relatively low speed. The solid liquid thus separated from the mixture is returned to the impeller chamber through the duct 23 leading out of the 30 separator.

When there is a minimum suction at the eye of the impeller chamber, that is, the inlet port 8, there is also a minimum pressure in the separator 21, and consequently a minimum 35 force urging flow of solid liquid through the duct 23 back into the impeller chamber. For maximum efficiency the quantity of liquid maintained in the impeller chamber under these conditions should be 40 such that the impeller will throw out just sufficient mixture to completely fill the discharge throat 12 with no excess. As the vacuum increases the pressure in the separator 21 either remains the same if the discharge 45 is open to atmosphere or increases if closed and the pressure difference on the opposite ends of the duct 23 is therefore increased in either event and the flow of liquid through it correspondingly increased. The 50 quantity of liquid in the impeller chamber is therefore increased and the proportions of air and liquid discharged thereby changed, and the impeller discharges more mixture than can be handled by the throat 12 and some 55 excess is discharged through the throat 44 as will presently appear. As the pressure difference between the opposite ends of the return duct increases the excess of mixture will likewise increase and some will tend to enter the 60 passage or throat 44 retarding or shutting off return flow through this passage or throat. If this does not compensate for the tendency to increase return flow by increase in pressure difference between separator and pump 65 casing, the amount of liquid in excess of that

going out the main throat 12 will be driven up through the passage or throat 44, thereby shutting off not only any return flow through throat 44 but throttling down by interference the return flow through passages 23 and 12. Thus there is an automatic and inherent 70 tendency to maintain approximate the return flow at a value which will give the maximum entraining ability.

When the runner 4 is rotating and a sufficient supply of liquid is present in the runner channel 3, to cause the runner to expel slightly more mixture than the throat 12 can carry, the excess is thrown through the passage formed by the wall 18 and the baffle 19, which 75 passage is substantially tangential to the runner 4 and through the other passageways between adjacent baffles if more than one baffle is used. The throat 44 of this passage is narrow and the passage is therefore completely sealed by this mixture. The presence 80 of mixture in the throat 44 obviously reduces the area through which returning liquid can flow and the return of liquid to the impeller chamber is thereby decreased. As the pressure difference between the separator and impeller chamber increases more liquid is returned to the impeller chamber and the quantity of mixture thrown into the throat 44 is 85 increased, that mixture being directed by the baffle 19 upwardly in the passageway 23 where it encounters the returning liquid and its pressure opposes the pressure of that returning liquid.

If the quantity of mixture is relatively small and its pressure correspondingly low, the solid liquid flowing downwardly in the passageway 23 will predominate and the mixture will not reach the separator but rather will be returned to the impeller chamber with the solid liquid. If the quantity of liquid in the impeller chamber is larger the quantity of mixture in the throat 44 will be greater and its pressure higher and this overflow of mixture will be thrown upward in the return passageway 23 with sufficient force to create a pressure opposing the flow of liquid from the separator into the runner chamber through the return passageway 46 by forming an eddy. This eddy obviously interferes with the return flow of liquid to the impeller chamber, and is, in effect, a throttle valve by which that return flow is governed. As the distance from the throat 44 increases the velocity of the mixture is diminished and its resistance to the flow of gas free liquid accordingly decreases. Usually the force of the mixture is overcome and the mixture stream is bent back toward the runner before the junction 47 of the return passage and separator is reached; however when the quantity of liquid in the channel is high, sufficient mixture will be thrown into the return passage to enable the stream of it to rise to the separator. The rising mixture and down traveling solid liq- 90 95 100 105 110 115 120 125 130

uid from the cylindrical wall section 26 again oppose each other at the junction of throat 23 and the separator forming in effect a valve which restricts the flow of solid liquid through the throat 23 and causes a portion of that liquid to continue in its travel in an arcuate path to the wall section 30 of the divider between the inlet and outlet passages of the separator. This cross flow of solid liquid across the opening 47 in effect screens that opening thereby preventing the down flow of mixture from the separator into the passage. The mixture thrown upward in the passage 23 by the runner 4 is entrained in this cross flow of liquid across the port 47 and squeezed between that liquid and the wall 30, which squeezing action facilitates the separation of gas from the mixture, which gas is permitted to rise in the separator and escape from the outlet port 37. If the velocity of the liquid across the wall section 30 is sufficient to carry that liquid completely across that wall, the liquid is caught in with the onrushing mixture through the inlet 22 of the separator and is whirled thereby, which whirling obviously materially assists in the liberation of gas from the mixture.

If a plurality of baffles 19 are inserted in the return passageway, the quantity of mixture carried by the passages between them decreases with number of passages intervening to the wall 18. Normally not all of the passages so formed will be filled with mixture and the unfilled ones are available to carry gas free liquid to the runner. If the quantity of excess mixture increases the number of passages filled by it increases and the number of passages left for the returning liquid decreases, so that the quantity of liquid returned to the runner is of course decreased. This throat action assists the hydraulic valve formed in the return passageway 23 in controlling the quantity of liquid returned to the runner.

Despite the fact that mixture is flowing upward through the passage 23, a stream of solid liquid will continuously flow downward through that passage along the walls 27 and 17, entering the runner channel through the radial passageway 46. The force of the mixture thrown into the auxiliary discharge port 44 is taken up by the baffle 19 and made to flow along the walls 18 and 29 of the passageway so that it causes a minimum of interference with the down flow of solid liquid until it reaches the discharge passageway 23 of the separator, where it forms the hydraulic valve hereinbefore mentioned. By this arrangement, a substantially constant return flow of gas free liquid from the separator to the channel is achieved and therefore a correct supply of liquid is at all times maintained in the runner channel so that the runner will always be supplied with sufficient liquid to enable it to entrain the maximum amount of

gas. The pump is therefore enabled to continuously increase the vacuum in its runner channel to thereby prime the pump. At no time is the quantity of returning liquid completely shut off and there is therefore no tendency for the pump to surge during its priming period.

As the vacuum on the suction face of the runner 4 increases the pressure in the separator also increases due to the pumping of mixture into it, and there is therefore a substantial pressure difference between the opposite ends of the passageways 23 and 46 so that there will be a tendency for more liquid to flow into the runner channel. This increase in the amount of liquid in the runner channel causes the runner to throw more mixture into the port 44, this mixture affording a greater opposing pressure to the returning liquid so that the flow of that returning liquid is thereby slightly diminished. This hydraulic valve action, more fully explained in my copending application Serial No. 461,313, filed June 16, 1930 (Case 32), accurately regulates the return flow so that the proper amount of liquid is at all times maintained in the runner channel and the proper ratio between volume of entrained gas and liquid is therefore always maintained, and the pump is therefore in condition for efficient priming.

Ordinarily the velocity of the solid wall of liquid flowing along the straight wall section 27 is so low that there is no tendency for the liquid to plunge into the passageway 23 under great pressure. However in certain instances the velocity of the liquid at the junction of the cylindrical wall 26 and the straight wall section 27 may be too high for efficient operation of the separator, which high velocity would tend to force too much liquid down into the throat 23 and prevent the free flow of mixture through the throat 47 with the result that the pump would soon become drowned and incapable of drawing further vacuum. To guard against contingencies of this kind in certain adaptations of my invention I contemplate providing the wall 27 with an inwardly depending arcuate boss 50, Figure 8, formed integral with the wall at the junction of the cylindrical section 26 and the straight section 27. The liquid traveling downward past this boss 50 is deflected upward out of the throat 47 leading into the passageway 23 and against the wall 30 striking that wall and being deflected upward thereby.

The end of the wall 30 adjacent the inlet passageway 22 of the separator may be extended upwardly as at 57 to deflect the liquid so thrown across the port 47 upward in the separator chamber 21 and against the upwardly moving stream of liquid against the wall 24 of the separator. In this embodiment of my invention, the stream of solid flowing crosswise of the throat 47 definitely

screens that throat from downwardly traveling mixture so that it is impossible for mixture to flow downwardly through that throat 47 and the passageway 23 into the runner 5 channel. This crosswise moving stream of solid liquid also serves as a support for the mixture of gas and liquid above it, that mixture being the inner stratum of the mixture thrown around the cylindrical wall 26, this 10 support holding the mixture in a relatively quiet position so that the gas can efficiently separate out of the mixture and pass out of the port pump through the discharge port 37.

15 The mixture expelled by the runner and carried through the auxiliary discharge throat 16 to the separator is carried transversely along the wall 30 by this cross flow and entered thereby into the stream of mixture flowing through throat 22. This mixture is of course squeezed between the wall 30 and the cross stream of gas free liquid and bent in an upward direction by the tip portion 57 of that wall so that when it enters 20 the upward stream of mixture it expands and the gas in it is thereby permitted to escape.

While I have chosen to illustrate my invention by showing a preferred embodiment of it, I have done so by way of example only 30 as there are many modifications and adaptations which can be made by one skilled in the art without departing from the teachings of the invention.

35 Having thus complied with the statutes and shown and described a preferred embodiment of my invention, what I consider new and desire to have protected by Letters Patent is pointed out in the appended claims.

40 What is claimed is:

1. In a centrifugal pump, a runner chamber, a rotatable runner therein, a throat leading tangentially out of said chamber, a separator connected to said throat and communicating therewith, a second throat leading from said separator to said chamber, and a dividing wall in said second throat separating it into a passage leading substantially tangentially to and a passageway leading 45 substantially radially of the chamber.

2. In a centrifugal pump of the self priming type, a runner chamber, a rotatable runner disposed in said chamber, a discharge throat leading from said chamber through 55 which said runner throws a mixture of gas and liquid during its priming period, a separator in which the gas in said mixture is liberated from the liquid, a return passage through which said liquid is returned to said 60 runner and through which excess mixture thrown from the runner is carried to the separator independently of said throat, and means in said passage for dividing the same into a passageway leading tangentially out 65 of said chamber and a passageway leading

radially into said chamber to prevent said mixture from mixing with said returning liquid.

3. In a centrifugal pump of the self priming type, a runner chamber, a rotatable runner disposed in said chamber, a discharge throat leading from said chamber through which said runner throws a mixture of gas and liquid during its priming period, a separator in which the gas in said mixture is liberated from the liquid, a return passage through which said liquid is returned to said runner during the priming period of the pump and through which excess mixture thrown from the runner is carried to the separator, and means in said excess passage for preventing said mixture from completely obstructing the flow of said returning liquid.

4. In a centrifugal pump of the self priming type, a runner chamber, a rotatable runner disposed in said chamber, a discharge throat leading from said chamber through which said runner throws a mixture of gas and liquid during its priming period, a separator in which the gas in said mixture is liberated from the liquid, a return passage through which said liquid is returned to said runner and through which excess mixture thrown from the runner is carried to the separator, and means in said excess passage for preventing said mixture from forming an eddy at the junction of said passage and chamber and completely obstructing the flow of said returning liquid.

5. In a centrifugal pump of the self priming type, a runner chamber, a rotatable runner disposed in said chamber, a discharge throat leading from said chamber through which said runner throws a mixture of gas and liquid during its priming period, a separator in which the gas in said mixture is liberated from the liquid, a return passage through which said liquid is returned to said runner and through which excess mixture thrown from the runner is carried to the separator, and baffle means in said return passage cooperating with the walls thereof for intercepting and directing the mixture thrown into the passage to cause it to throttle and regulate the flow of said returning liquid.

6. In a centrifugal pump of the self priming type, a runner chamber, a rotatable runner disposed in said chamber, a discharge throat leading from said chamber through which said runner throws a mixture of gas and liquid during its priming period, a separator in which the gas in said mixture is liberated from the liquid, walls defining a return passage through which said liquid is returned to said runner and through which excess mixture thrown from the runner is carried to the separator, and means in said passage cooperating with the walls thereof for maintaining the flow of mixture in a path

substantially tangentially to and the flow of liquid substantially radially of said runner adjacent to it to prevent surging of the pump during its priming stage.

5 7. In a centrifugal pump of the self priming type, a runner chamber, a rotatable runner disposed in said chamber, a discharge throat leading from said chamber through which said runner throws a mixture of gas and liquid during its priming period, a separator in which the gas in said mixture is liberated from the liquid, a return passage through which said liquid is returned to said runner and through which excess mixture thrown from the runner is carried to the separator, and baffle means located in said return passage and cooperating with the walls thereof for intercepting and directing the mixture thrown into it by said impeller to regulate the pump during its priming period.

8. In a self priming centrifugal pump, the combination of a pump casing, a runner mounted therein and adapted to be rotated about a horizontal axis, a throat leading upward tangentially of said casing, said throat carrying the mixture of gas and liquid discharged by said runner during the priming period of the pump, a separator communicating with said throat, said separator having means for bending the stream of mixture in an arcuate path about an axis parallel to the axis of the runner to stratify it and bring a stratum of solid liquid above a stratum of mixture, lateral ports through which the gas in said mixture stratum is permitted to escape, a return passage leading from said separator into said casing radially of said runner, and means in said separator for deflecting said stratum of solid liquid across said return passageway to screen it from said mixture.

9. In a self priming centrifugal pump, the combination of a pump casing, a runner mounted therein and adapted to be rotated about a horizontal axis, a throat leading upward tangentially of said casing, said throat carrying the mixture of gas and liquid discharged by said runner during the priming period of the pump, a separator communicating with said throat, said separator having means for bending the stream of mixture in an arcuate path about an axis parallel to the axis of the runner to stratify it and bring a stratum of solid liquid above a stratum of mixture, a lateral port through which the gas in said mixture stratum is permitted to escape, a return passage leading from said separator into said casing radially of said runner, and means in said separator for deflecting said stratum of solid liquid across said return passageway in a plane below said stratum of mixture to cause it to screen the passageway from said mixture and to support the mixture so that the gas in it may rise and escape through said lateral ports.

10. In a self priming centrifugal pump, the combination of a pump casing, a runner mounted therein and adapted to be rotated about a horizontal axis, a throat leading upward tangentially of said casing, said throat carrying the mixture of gas and liquid discharged by said runner during the priming period of the pump, a separator communicating with said throat, said separator having means for bending the stream of mixture in an arcuate path about an axis parallel to the axis of the runner to stratify it and bring a stratum of solid liquid above a stratum of mixture, lateral ports through which the gas in said mixture stratum is permitted to escape, and a return passage leading tangentially from said separator into said casing radially of said runner and a branch of said return passageway leading tangentially out of said casing to convey excess mixture expelled by the runner into said separator.

11. In a self priming centrifugal pump, a casing, a runner disposed in said casing and rotatable about a horizontal axis, a discharge throat in said casing leading upward tangentially of said runner, a separator connected to said throat, said separator consisting of a flat wall aligned with said throat, a cylindrical wall disposed with its axis parallel to the axis of said runner and having one of its ends aligned with said flat wall, a second flat wall aligned with the opposite end of said cylindrical wall and disposed at an angle with respect to said first flat wall, a return throat in said casing having a wall aligned with said second flat wall and disposed radially of said runner, and side walls on said separator joined with said flat and cylindrical walls and having discharge ports adjacent said cylindrical walls.

12. In a self priming centrifugal pump, a casing, a runner disposed in said casing and rotatable about a horizontal axis, a discharge throat in said casing leading upward tangentially of said runner, a separator connected to said throat, said separator consisting of a flat wall aligned with said throat, a cylindrical wall disposed with its axis parallel to the axis of said runner and having one of its ends aligned with said flat wall, a second flat wall aligned with the opposite end of said cylindrical wall and disposed at an angle with respect to said first flat wall, a return throat in said casing having a wall aligned with said second flat wall and disposed radially of said runner, side walls on said separator joined with said flat and cylindrical walls and having discharge ports adjacent said cylindrical walls, and a triangular wall section disposed between said side walls and separating said discharge and return throats.

13. In a self priming centrifugal pump, a casing, a runner disposed in said casing and rotatable about a horizontal axis, a discharge

- throat in said casing leading upward tangentially of said runner, a separator connected to said throat, said separator consisting of a flat wall aligned with said throat, a cylindrical wall disposed with its axis parallel to the axis of said runner and having one of its ends aligned with said flat wall, a second flat wall aligned with the opposite end of said cylindrical wall and disposed at an angle with respect to said first flat wall, a return throat in said casing having a wall aligned with said second flat wall and disposed radially of said runner, side walls on said separator joined with said flat and cylindrical walls and having discharge ports adjacent said cylindrical walls, and a discharge duct located above said cylindrical wall and communicating with said discharge ports.
14. In a self priming centrifugal pump, a casing, a runner disposed in said casing and rotatable about a horizontal axis, a discharge throat in said casing leading upward tangentially of said runner, a separator connected to said throat, said separator consisting of a flat wall aligned with said throat, a cylindrical wall disposed with its axis parallel to the axis of said runner and having one of its ends aligned with said flat wall, a second flat wall aligned with the opposite end of said cylindrical wall and disposed at an angle with respect to said first flat wall, a return throat in said casing having a wall aligned with said second flat wall and disposed radially of said runner, side walls on said separator joined with said flat and cylindrical walls and having discharge ports adjacent said cylindrical walls, and hollow semi-cylindrical bosses raised out of said side and cylindrical walls to form a discharge duct located above said separator and communicating with said discharge ports.
15. In a self priming centrifugal pump, a casing, a runner disposed in said casing and rotatable about a horizontal axis, a discharge throat in said casing leading upward tangentially of said runner, a separator connected to said throat, said separator consisting of a flat wall aligned with said throat, a cylindrical wall disposed with its axis parallel to the axis of said runner and having one of its ends aligned with said flat wall, a second flat wall aligned with the opposite end of said cylindrical wall and disposed at an angle with respect to said first flat wall, a return throat in said casing having a wall aligned with said second flat wall and disposed radially of said runner, side walls on said separator joined with said flat and cylindrical walls and having discharge ports adjacent said cylindrical walls, a triangular

wall section disposed between said side walls and separating said discharge and return throats, and an arcuate boss projecting inwardly from the junction of said cylindrical and second flat walls to deflect liquids hugging said wall across the opening of said return throat and against said triangular wall section.

16. A pump casing containing a cylindrical runner channel and having a projection forming a discharge throat of small cross sectional area at the junction of the channel and throat, the walls on three sides of said throat flaring to increase the cross sectional area of said throat, the wall on the fourth side of the throat being tangential to said channel, a return throat formed in said projection by one flaring wall of said discharge throat and the walls of said projection, said flaring wall being tangential to the channel on the side forming said return throat and said projection walls being radial of said channel, and a baffle wall in said return throat dividing it into two passageways which lead into the channel.

17. In a self priming pump, the combination of a pump casing containing a runner chamber, a discharge leading tangentially out of said chamber, a cylindrical separator attached to said casing and disposed with its axis horizontal and above the axis of said chamber, an entrance passage for said separator, said passage connecting with said discharge throat and leading substantially tangentially into said separator, a port leading out of said separator, a return passageway leading from said separator into said chamber, and means in said return passageway cooperating with the walls thereof for regulating the flow of liquid through it during the priming period of said pump.

18. In a self priming pump, the combination of a pump casing containing a runner chamber, a discharge leading tangentially out of said chamber, a cylindrical separator attached to said casing and disposed with its axis above the axis of said chamber, an entrance passage for said separator, said passage connecting with said discharge and leading substantially tangentially into said separator, a port leading out of said separator, a return passageway leading from said separator into said chamber, and baffle means in said return passageway cooperating with the walls thereof for regulating the flow of liquid through it during the priming period of the pump.

In witness whereof, I hereunto subscribe my name this 21st day of July, 1930.

HARRY E. LA BOUR.

CERTIFICATE OF CORRECTION.

Patent No. 1,915,678.

June 27, 1933.

HARRY E. LA BOUR.

It is hereby certified that error appears in the printed specification of the above numbered patent requiring correction as follows: Page 6, lines 81 and 95, claims 3 and 4, strike out the word "excess" and insert the same after "said" in lines 82 and 96, respectively; and that the said Letters Patent should be read with these corrections therein that the same may conform to the record of the case in the Patent Office.

Signed and sealed this 15th day of August, A. D. 1933.

M. J. Moore.

(Seal)

Acting Commissioner of Patents.
